UNITED STATES PATENT OFFICE.

CLARENCE W. PEASE, OF PADUCAH, KENTUCKY, ASSIGNOR TO INTERNATIONAL SHOE COMPANY, OF ST. LOUIS, MISSOURI, A CORPORATION OF DELAWARE.

MACHINE FOR FORMING HEEL SEATS AND TOES OF SHOES.

Application filed January 22, 1925. Serial No. 4,074.

This invention relates to machines for forming the heel seats and toes of shoes.

An object of the invention is to provide a machine by use of which the work of forming the heel seats and toes of shoes is greatly expedited and the cost of manufacture largely reduced, and by use of which a better and more refined article is obtained in respect of the formation of the heel seats and toes.

Another object is to provide a machine operative at a single operation to obtain the two results (one) of forming either the heel seats or the toes of shoes and (two) adhesively uniting the uppers and the soles artistically and in accurate conformation to the lasts in order to dispense with the use of staples and other fastening elements heretofore generally used to secure the uppers and soles together, preparatory for subsequent stitching operations.

Other objects will appear from the following description, reference being made to the drawings in which—

Fig. 1 is a plan view of the machine.

Fig. 2 is a side elevation.

Fig. 3 is a cross sectional view on the line 3—3 of Fig. 2.

Fig. 4 is a sectional view showing a part of the electric circuit structure by which the heater is electrically heated.

Fig. 5 is a sectional view showing the relationship of the parts in operating to form the toe of a shoe.

The operative mechanism of the machine is supported by a frame 1 having a work supporting table 2 at its upper end upon which the shoes are placed when being subjected to the action of the machine.

An extension 3 from one side of the table may be provided to support the inner toe caps or other shoe parts to be embodied in shoes upon which this machine operates. Between the table 2 and the extension 3

a heated support 4 is shown, an electric heater being conventionally shown therein in dotted lines and heated by electric circuit wires 5 controlled by a switch 6. In the manufacture of shoes for small children the inner toe caps A (Fig. 5) are sometimes of a composition material containing or carrying an adhesive substance which becomes softened and viscid under heat of about one hundred and fifty degrees, Fahrenheit, more

or less, so that when the toe caps are placed or on the toe caps A, and the heated presser

in position to be secured in the toes of the shoes the adhesive substance on the edges of the toe caps between the edges of the uppers and of the soles forms a connection securing the edges of the uppers and the edges of the soles in proper relationship.

The present machine is specially designed and adapted for use in the manufacture of shoes of that type in which the toe and the heel portions of the uppers are smoothed against the extremities of the lasts and secured to the soles. Heretofore it has been the general practice to utilize fasteners, either wire staples or other similar devices which interfered seriously with the operation of the awls and stitching devices when the stitches were applied to fasten the uppers and soles together permanently. By the present invention, which includes a heated presser for pressing the edges of the toe and heel portions of the uppers smoothly upon the soles with interposed adhesive material, the necessity of using staples or other fastening elements is eliminated, the extended portions of the uppers being smoothed and bonded to the soles ready for the application of the stitches to complete the shoes. The table 2, which is relatively close to the heated presser, is separated from bordering table portions 7 which are insulated from the heated table 2 by intervening spaces, as shown.

The presser comprises a heated metallic plate 8 attached to the upper end of a rotative and vertically movable shaft 9. The plate 8 is heated by an electric heater 10 to which electric current is supplied from wires 11 and 12 controlled by the switch 6. A bracket 13 supports a terminal contact member 14 for the wire 11 and a terminal contact member 15 for the wire 12, said contact members being mounted on a supporting bolt 16 and insulated therefrom and from each other. A wire 17 leading to the heater 10 is in circuit with the wire 11 through a spring member 18 contacting with the contact member 14; and a wire 19 leading to the heater is in circuit with a wire 12 through a spring member 20 contacting with the contact member 15. Thus when the switch 6 is closed both the heated support 4 and the presser plate 8 are electrically heated. The heated support 4 conditions for use the adhesive material in or on the toe caps A, and the heated presser

plate 8 will press and smooth the extended heel and toe portions of the shoe uppers upon the soles and adhesively secure them thereto.

- 5 The presser plate 8 is provided with a number of series of recesses in its side edge or edges. In the embodiment shown there are four series of recesses and four recesses in each series, of which the recesses 21 are 10 the heel receiving recesses and the recesses 22 are the toe receiving recesses. Four recesses are needed in each series to operate upon the toes and heels of a pair of shoes. The pairs of recesses 21 and also the pairs 15 of recesses 22 are of graduated sizes corresponding to the different sizes of shoes, so that as shown each side edge of the presser plate is constructed to complete the work upon the heels and toes of pairs of 20 shoes of a certain size different from the size of shoes worked upon by another side edge of the presser plate.

An arm 23 is attached to an insulation block 24 that supports the binding posts for 25 the wires 17 and 19 and the spring members 18 and 29, and which is rotative on the bolt 16. A rod 25, extending from the insulation member 26 on the shaft 9, extends through a hole in the arm 23 so that the arm 30 23 and the block 24 will be turned with the plate 8. Thus, irrespective of the position of the presser plate, the circuit wires 11 and 12 are at all times in circuit with the heater 10.

35 A disc 27 supported upon a frame part 28 is splined to the shaft 9, so that the shaft may move longitudinally through but cannot turn independently of said disc. The disc 27 has four peripheral notches 29 corresponding to the four side edges of the presser plate 8. A latch detent 30 is actuated by a spring 31 to engage the notches 29, respectively, and thereby hold the shaft 9 and the presser plate 8 from turning. Thus the 40 presser plate may be latched in position to retain any selected side edge thereof toward the operator for continuous work upon shoes of a certain size, and may be turned to present any other side edge to the operator 45 when shoes of a different size are to be worked upon. A lever 32 is operative to release the latch 30 from any notch 29 to permit the shaft 9 to be turned, as stated.

50 55 A link device 33 has swivel connection 34 with the lower end of the shaft 9 and also has connection with a treadle lever 35 where by the shaft 9 is moved downwardly to press the heated presser plate upon and to render 60 smooth and to adhesively bond the heel and toe upper portions to the shoe soles. A spring 36 encircles the shaft 9 between the disc 27 and a collar 37 and operates to raise the shaft 9 and thereby the heated presser plate when the treadle lever 35 is released.

In operation the toe caps containing or carrying adhesive substance are moved from the table extension 3 to the heated support 4, upon which the adhesive substance becomes viscid and the toe caps are readily 70 pliable. The operator places a toe cap upon the toe of the last in the shoe upon which he is working and presses the upper upon the toe cap and, by manipulation, shapes the toe cap and the upper to conformity with 75 the toe of the last, causing the edge of the toe cap to seat upon the edge of the sole and the edge of the upper to seat upon the edge of the toe cap, and the edges of said three shoe elements to become bonded together by the adhesive substance in the toe cap. This manipulation also causes that 80 portion of the toe cap, the inner surface of which bears against the toe of the last, to become adhesively bonded to the inner side 85 of the upper. After properly shaping the toe cap and the toe portion of the upper, as described, the operator places the toe of the shoe in one of the recesses 22 and operates the treadle lever 35, with the result that 90 the heated presser plate 8 is pressed upon the edge of the toe portion of the upper, which is the uppermost one of the three superimposed shoe elements. This pressure by the heated presser plate smooths out the 95 wrinkles and creases in the leather and securely bonds the three superimposed edges of the shoe elements together.

The heel seat of the shoe is formed by 100 placing the heel of the shoe in one of the recesses 21 and then depressing the presser plate 8 upon the extended edge of the heel portion of the upper, with the result that the upper is adhesively united to the heel portion of the sole with sufficient strength 105 to retain the connection until the shoe is completed by stitching the parts together in the usual manner.

110 It is apparent that the foregoing operations may be rapidly performed upon my machine, and experience has demonstrated that the output of a single workman is vastly increased over that which was possible by the old method consisting in the use of any device to shape the shoe upper in conformity with the last and then uniting the shoe elements by staples or other fastening devices, for the purpose of holding them together until the stitches were applied. In 115 factories having a relatively large output the saving is great; because the cost of manufacturing the shoes is greatly reduced, they are completed with greater speed, the output of each workman is greatly enlarged, 120 and difficulties in sewing are avoided.

125 My invention obtains all of its intended objects and purposes in an efficient manner. It is obvious that it may be varied widely without departure from the nature and principle of the invention.

What I claim and desire to secure by Letters Patent is:—

1. In a machine of the character described comprising a table, a presser plate having a number of recesses arranged to receive the ends of shoes, means for supporting said plate in different adjustments in which selected ones of said recesses are toward one side of the table, and means for operating said plate toward and away from said table.
2. A machine of the character described comprising a support mounted for longitudinal and turning movements, a presser plate attached to said support and having a number of recesses in its edges conforming to the shapes of heel seats and toes of shoes, means for holding said support in position in which selected ones of said recesses are toward the operator, a table for supporting shoes with the heel seats and toes in said recesses, and means for operating said support to press said plate against the heel seats and toes of said shoes.
3. A machine of the character described comprising a shaft mounted for longitudinal and turning movements, a device holding said shaft from accidental turning and permitting longitudinal movements of said shaft, a presser plate attached to said support and having a number of recesses in its edge conforming to the shapes of heel seats and toes of shoes, means for holding said support in position in which selected ones of said recesses are toward the operator, a table for supporting shoes with the heel seats and toes in said recesses, mean for operating said support to press said plate against the heel seats and toes of said shoes, and an electric heater in connection with said plate.
4. A machine of the character described comprising a table, a vertical shaft mounted for longitudinal and turning movements and extending above said table, a plate attached to said shaft above said table and having recesses in an edge thereof conforming to the shapes of the toes of a pair of shoes of one size and having recesses in another edge thereof conforming to the shapes of the toes of a pair of shoes of another size, means for holding said shaft and said plate in positions in which selected ones of said recesses are toward the operator, and devices for operating the shaft to raise and lower the plate.
5. A machine of the character described comprising a table, a shaft extending above said table for longitudinal and turning movements, a plate attached to said shaft above said table having a series of recesses in one side edge conforming to the shapes of the heel seats and toes of a pair of shoes of one size and having a series of recesses in another side edge thereof conforming to the shape of heel seats and toes of a pair of shoes of another size, a device cooperating with said shaft to hold said plate in position in which either series of recesses are toward the operator, means for maintaining said plate in a heated condition, and devices for operating the shaft to raise and lower the plate.
6. A machine of the character described comprising a table, a shaft extending above said table for longitudinal and turning movements, a plate attached to said shaft above said table having a series of recesses in one side edge arranged to receive the ends of a pair of shoes of one size and having a series of recesses in another side edge thereof arranged to receive the ends of a pair of shoes of another size, a device cooperating with said shaft to hold said plate in position in which either series of recesses are toward the operator, means for moving said shaft longitudinally to press said plate against the shoes in said recesses, a connection permitting turning of said shaft relative to said means, an element for moving said shaft in a direction to remove said plate from the shoes, and means for heating said plate.
7. A machine of the character described comprising a table, a support at one side of said table, means for heating said support, a shaft extending through said table for longitudinal and turning movements, a plate attached to said shaft above said table having a series of recesses in one side edge conforming to the shapes of the heel seats and toes of a pair of shoes of one size and having a series of recesses in another side edge thereof conforming to the shape of heel seats and toes of a pair of shoes of another size, means for actuating said shaft to press said plate against the heel seats and toes of shoes located in said recesses, means for maintaining said plate in a heated condition, and means cooperating with said shaft to hold said plate in position in which either series of said recesses is toward the operator.
8. A machine of the character described comprising a table, a shaft extending through said table, a plate rigidly attached to said shaft above said table having a series of recesses in an edge thereof corresponding to the shape and size of the heel seats and toes of a pair of shoes, means for moving said shaft downwardly to press said plate against the heel seats and toes of shoes positioned in said recesses, and means for raising said shaft to release said plate from the heel seats and toes of said shoes.
9. A machine of the character described comprising a table, a shaft extending through said table, a plate rigidly attached to said shaft above said table having a series of recesses in an edge thereof corresponding to the shape and size of the heel seats and toes of a pair of shoes, means for

- moving said shaft downwardly to press said plate against the heel seats and toes of shoes positioned in said recesses, means for raising said shaft to release said plate from the 5 heel seats and toes of said shoes, and means for maintaining said plate in a heated condition.
10. A machine of the character described comprising a table, a shaft extending through said table for longitudinal and turning movements, a plate attached to said shaft above said table having a number of series of recesses in its edges of which each series corresponds to the shape and size of 15 the heel seats and toes of a pair of shoes of a size different from the size of shoes to which the recesses in the other side edges of said plate correspond, means for holding said shaft in position in which either 20 series of recesses is toward the operator at one side of the table, and means for operating said shaft to press said plate against the heel seats and toes of shoes extending into said recesses.
25. 11. A machine of the character described comprising a table, a shaft extending upwardly through the top of the table, a presser plate rigidly attached to the shaft above the top of the table and having recesses formed therein corresponding to the shapes of the toes of shoes, means supported below the table for moving said shaft downwardly to press said plate against the toes of shoes in said recesses, and a device supported below the table for raising said shaft to move said plate from the toes of shoes in said recesses.
30. 12. A machine of the character described comprising a table, a shaft extending through said table for longitudinal and turning movements, a polygonal plate attached to said shaft above said table and having a series of recesses in each of a number of side edges thereof, of which each series corresponds in shape and size to the shapes of heel seats and toes of a pair of shoes of a size different from the recesses in any other side edge of said plate, means for holding said shaft in position in which either series of recesses is toward the operator at one side of the table, means for heating said plate, and means for operating said shaft to press said plate against the heel seats and toes of shoes in said recesses.
35. 13. A machine of the character described comprising a table, a support, a plate attached to said support and having a series of recesses in each of a number of side edges thereof, means for holding said support in position in which either series of recesses is toward the operator at one side of the table, and means for actuating said support to press said plate against the heel seats and toes of shoes in said recesses.
14. A machine of the character described 65 comprising a table, an element supported for reciprocating and turning movements, a plate attached to said element above said table and having a number of recesses corresponding to the size and shape of the toes of shoes, means for holding said element in position in which selected ones of said recesses are toward the operator at one side of the table, and a device for moving said element in one direction to press said plate 70 against toes of shoes in said recesses and in another direction to move said plate from the toes of said shoes.
15. A machine of the character described comprising a table, a presser plate above 80 said table and having recesses corresponding to the shape and size of the toes of a pair of shoes, a longitudinally movable shaft having rigid connection with and supporting said plate, means for operating said shaft in one direction to press against the toes of shoes in said recesses and in another direction away from the toes of said shoes, a heater in connection with said plate; a bracket extending over said table and said 85 plate, and electric circuit connections supported by said bracket for conducting electrical energy to said heater.
16. A machine of the character described 90 comprising a table, a shaft supported by said table for longitudinal and turning movements, a plate attached to said shaft above said table and having a series of recesses in each of a number of side edges thereof to receive the heels and toes of 95 shoes, a latch device for holding said shaft in position in which either series of said recesses is toward one side edge of said table, means for releasing said latch device to permit said shaft to turn to position to 100 present any selected series of recesses toward said side of said table, and manipulative means for pressing said plate against the toes of shoes in said recesses.
17. A machine of the character described 105 comprising a table, a shaft supported by said table for longitudinal and turning movements, a plate attached to said shaft above said table and having a series of recesses in each of a number of side edges 110 thereof to receive the heels and toes of shoes, a latch device for holding said shaft in position in which either series of said recesses is toward one side edge of said table, means for releasing said latch device to permit said shaft to turn to position to 115 present any selected series of recesses toward said side of said table, manipulative means for pressing said plate against the toes of shoes in said recesses, and automatic 120 means for operating said shaft to move said plate from the toes of shoes in said recesses.
